UNITED STATES PATENT OFFICE

CHARLES W. ANDREWS, OF CHICAGO, ILLINOIS, ASSIGNOR TO H. A. BRASSET & COMPANY, OF CHICAGO, ILLINOIS, A CORPORATION OF ILLINOIS

CHARGING BELL CONSTRUCTION

Application filed January 20, 1928. Serial No. 243,149.

This invention relates to a new and improved blast furnace charging bell construction and more particularly to a construction of this character adapted to more uniformly distribute the material over the furnace area than bells of the usual type.

Blast furnaces and similar furnaces are very generally charged by means of a double bell system, the charge being held between two bells and passed into the top of the furnace by lowering the lower and larger bell. A wide variety of means have been invented in the endeavor to distribute a charge uniformly about the circumference of the furnace. These means serve to insure that substantially equal portions of the charge are introduced into each portion of the periphery of the furnace but they do not effect a uniformity of the charge throughout the cross sectional area of the furnace.

The usual bells shoot the charge off of their sloping surfaces against the sides of the furnace. The large lumps are deflected from the sides of the furnaces and roll back toward the center directly under the bell, which center portion of the charge is usually low. The finer material remains adjacent the sides where it is delivered by the bell. This has the result of making the center of the furnace much more permeable and open for the passage of the gases through the furnace and results in uneven burning and working of the furnace charge. These inequalities would be obviated if it were possible to substantially evenly distribute the fine and coarse material over the entire cross sectional area of the furnace charge as the gases would then pass up evenly throughout the charge and the charge itself would travel down the furnace more evenly. This would result in smoother operation of the furnace and less production of flue dust.

According to the present invention this more even distribution is accomplished by the use of a hopper ring which engages the charging bell at a point spaced from the periphery of the bell. The bell is made to extend a variable distance beyond the line of engagement with the hopper ring at different points in the periphery of the bell. While

many such forms of construction are possible to carry out this invention, the preferred form consists in having the edge of the bell in the form of a spiral or helix. The beginning of the helix is located closely adjacent the line of the engagement between the hopper ring and the charging bell and the outer end of the helix will be located radially outward from the line of the hopper ring any desired distance, depending upon the size and operation of the parts. The bell is rotated progressively during the operation of the furnace.

It is an object of the present invention to provide a new and improved charging bell construction adapted to substantially evenly distribute the charged material throughout the cross sectional area of the furnace.

It is an additional object to provide a construction of this character in which the charging bell itself is progressively rotated as the furnace is charged.

It is also an object to provide a construction of this character which is simple in design and operation, and adapted for commercial production and installation without material change in existing structures.

Other and further objects will appear as the description proceeds.

I have illustrated a preferred embodiment of my invention in the accompanying drawings, in which

Figure 1 is a fragmentary sectional view showing my improved bell construction applied to the top of a blast furnace;

Figure 2 is a plan view of the charging bell; and

Figure 3 is a plan view on an enlarged scale showing the ratchet bell rotating mechanism.

Referring first to Figure 1, the top of the blast furnace shell is shown at 11 and the lining at 12. The hopper ring 13 is secured to the top of the shell 11 to which is also connected the hopper housing plates 14. In the form shown the charging chute 15 is rotated by means of the gears 16 and motor 17 in order to give a better distribution of the material throughout the circumference of the furnace. The charging material is delivered to the chute 15 by means of the charging skip 18.

18 running on tracks 19. It will be understood that the construction so far described is of a usual type with the exception that the hopper ring 13 is so designed as to meet the 5 large charging bell upon a smaller circle than is customary in usual constructions.

The large charging bell 20 is suspended from the hanger rod 21 and the small charging bell 22, which cooperates with the bottom section 23 of the charging chute, is hung from the sleeve 24 in the usual manner. It 10 will be understood that usual forms of apparatus will be provided for raising and lowering the smaller charging bell and such devices have not been shown as they form no part of the present invention.

The hanger rod 21 of the larger bell is extended through the steam cylinder 25 and through the ratchet sleeve 26. The ratchet 20 sleeve 26 is rotatably fitted upon the top of the cylinder 25. The piston 27 is carried upon the rod 21 within the cylinder 25 and any usual connections may be provided for admitting steam into the cylinder to force the 25 piston upwardly and thus close the larger bell 20 against the hopper ring 13. The bell is dropped by releasing the steam pressure under the piston. The rod 21 is provided with the arm 28, as best shown in Figure 3, 30 this arm 28 fitting into the spiral groove 29 formed in the ratchet sleeve 26. The sleeve 26 is provided with teeth 30 which are engaged by the spring pressed pawl which is carried on lug 32.

The lower edge 33 of the charging bell 20 is formed spirally in outline, as best shown in Figure 2. Since the bell 20 is pivotally supported on the rod 21, it is highly desirable to have it balanced about its pivot point and for 40 that reason the lower edge is thickened with a counterbalancing bead upon its inner side. This bead will be increased in thickness and weight as the width of the bell portion beyond the line of contact with the hopper ring 45 decreases in radial extent. The hopper bell will therefore be of substantially equal weight throughout its circumference and will hang properly from the rod 21 so as to uniformly engage the lower edge of the hopper 50 ring 13.

In the use of the charging apparatus it will be understood that the charging material is introduced through chute 15 and will pass down through the chute and be distributed 55 into the hopper formed above the large bell 20 by means of the small bell 22. The chute 15 may be rotated to make this distribution more uniform throughout the circumference 60 of the hopper. When it is desired to introduce a charge into the furnace the small bell 22 is raised and closes the lower end of the chute 15. The large bell is then lowered by releasing the pressure in the steam cylinder 25. As the bell separates from the edge of 65 the hopper ring 13, material will flow down

between the ring and the bell into the top of the furnace. This material will be guided in its flow by the lower flange of the bell and will be guided different distances towards the outer furnace wall at different circumferential points due to the difference in the radial extent of the bell. All of the material will thus not be shot directly against the lining walls as in usual forms of construction, but will be distributed throughout a large portion 70 of the furnace area.

As the bell moves downwardly the rod 21 will move downwardly, carrying downwardly the arm 28. This downward movement of the arm 28 will force the ratchet sleeve 26 to rotate in the clockwise direction, as seen in Figure 3. This is for the reason that the sleeve will rotate much more easily than the entire bell and rod assembly. This rotation of the sleeve will be permitted by the spring 80 pawl 31 which will ride over the teeth upon rotation in this direction.

After the charge has entered the furnace, the bell 20 will be raised by the introduction of steam or other fluid under pressure into 90 cylinder 25. As the rod 21 rises it will force the arm 28 upwardly in the groove 29 of the ratchet sleeve 26. This will tend to force the sleeve in the counterclockwise direction but such movement of the sleeve is prevented by 95 the spring pressed pawl 31. The arm 28 and groove 29 will thus serve to rotate the rod 21 and bell 20. In the form shown, this rotation is approximately a quarter of the circle. It will be understood that the slope of the 100 groove 29 may be modified to give any desired amount of rotation of the bell with each charging movement of the bell.

While I have shown one preferred form of my invention, it is capable of further changes and modifications to meet varying conditions of service and to adapt it for use with different constructions, and I contemplate such changes and modifications as come within the spirit and scope of the appended claims.

I claim:

1. In a blast furnace, a charging bell located interiorly of the top of the furnace, a hopper ring in the furnace having a circular opening, the bell having a downwardly curved upper portion having a similar contour on all diameters, said upper portion engaging the circular opening in the hopper, an extended downwardly sloping portion on the bell extending beyond the line of contact with the hopper, said extended portion varying in width throughout its circumference and having a helical lower edge, and counterbalance means on the inner face of the extended portion whereby the bell is balanced about 115 its central upper portion.

2. In a blast furnace, a charging bell located interiorly of the top of the furnace, a hopper ring in the furnace having a circular opening, the bell having a downwardly 120

curved upper portion having a similar contour on all diameters, said upper portion engaging the circular opening in the hopper, an extended downwardly sloping portion on the bell extending beyond the line of contact with the hopper, said extended portion varying in width throughout its circumference and having a helical lower edge, counterbalance means on the inner face of the extended portion whereby the bell is balanced about its central upper portion, and means whereby the bell is rotated progressively during its operation.

Signed at Chicago, Illinois, this 16th day
15 of January, 1928.

CHARLES W. ANDREWS.
